Chicago, Ill.

Filed Nov. 24, 1961, Ser. No. 67,721

Term of patent 14 years

(Cl. D55—1)

FIG. 1 is a front and right side perspective view of an automatic machine for folding garments and other flexible articles embodying my new design;

FIG. 2 is a front perspective view thereof taken from a point slightly below the level of FIG. 1;

FIG. 3 is a perspective view taken on the same level as FIG. 2 and from the side opposite thereof;

FIG. 4 is a perspective view taken from the right side and on approximately the same level as FIG. 3; and

FIG. 5 is a perspective view taken from the right side on a level slightly below that of FIGS. 3 and 4.

I claim:

The ornamental design for an automatic machine for folding garments and other flexible articles, substantially as shown.
